FEED FINGER

Stoddard B. Martin, Lakewood, Ohio

Application November 23, 1936, Serial No. 112,437

5 Claims. (Cl. 29—61)

My invention relates to improvements in feed fingers for feeding bar stock in hand or automatic screw machines or the like.

An object of the present invention is to provide a positive, yet structurally simple means for intermittently feeding rod or bar stock into the path of a tool.

A further object resides in providing a self releasing stock gripping member which is so constructed that centrifugal force automatically operates the member to grip the stock when the rotating feed tube is moved in one direction, but which will release its grip on the stock when the tube is at rest or moves in an opposite direction.

Another object of the invention is to provide a stock gripping means comprising an annulus which is movable relatively to the stock when one of the side walls of the annulus is in a substantially vertical plane, but which grips the stock when another of its walls approaches the vertical.

A still further object of the invention is to provide a feed finger with means for intermittently gripping the stock passing therethrough wherein said means includes a normally loose annulus within the pusher tube and is adapted to shift its position with respect to the tube and stock upon rotation of the tube whereby to grip the stock as the tube is moved axially in one direction to feed the stock for a cutting operation.

Another object is to provide such a gripping device which may be released upon a reversal of movement of the tube.

Other objects and advantages of my invention will become more apparent from the following description of an embodiment thereof, reference being made to the accompanying drawing in which like reference characters are employed to designate like parts throughout the same.

In the drawing:

Figure 1 is a longitudinal section through a feed finger for screw machines showing my invention in use and the gripping annulus freely resting on the stock, as when the tube is at rest or when the tube is retracted in the direction of the arrow.

Figure 2 is a view similar to that of Figure 1, but shows the annulus gripping the stock as the feed tube rotates and moves forward in the direction of the arrow to feed the stock forward.

Figure 3 is a section taken on line 3—3 of Figure 2, and,

Figure 4 is a perspective view of the gripping annulus.

Referring to the drawing in detail which illustrates one form of my invention, the feed or pusher tube is indicated at 1. The outer end of the tube is counterbored for a portion of its length at 2 to readily and removably receive the gripping annulus 3, the bushing 4 and the retaining member 5. The retaining member is in the form of a split resilient ring which is seated in an annular groove or recess 6 formed in the counterbore of the tube 1 and functions to retain the bushing 4 and the gripping annulus 3 within the compartment 2 when the device is in use.

A second bushing (not shown) may be located on the opposite side of the annulus 3 if desired.

As will be seen from the drawing, the bar stock 7 passes through the tube and the members 3, 4, and 5, and is fed forwardly to a position where it may be acted upon by a tool in the usual manner.

By my invention I have provided means which depends upon centrifugal force and/or axial movement of the tube for its operation. This means includes an annulus or ring of hardened metal, the side or transverse walls of which preferably lie in intersecting planes. Thus it will be seen that the thickness of the ring at certain diametrically opposite point will be at a maximum on one side and at a minimum at the opposite side.

When the ring is assembled in the tube, the side wall 10 normally lies in a vertical plane while the opposite wall 11 lies in a plane intersecting the vertical and the annulus loosely encircles the stock as shown in Figure 1. Thus the bar stock has freedom of movement axially in the tube 1 and the annulus, as when the tube is at rest or is moved to the left in Figure 1. However, when the tube and annulus are rotated, the centrifugal forces set up in the annulus will tend to shift the heavy side of the annulus or ring outwardly to the position shown in Figure 2 and the ring is thus tilted slightly to the right, there being but a small annular clearance between the ring and the stock. When the ring is in this position, one edge 12 along its lower or thinner portion may be thrust into contact with the outer surface of the stock and the edge 14 will be lowered to gripping engagement with the stock and, as the tube moves forward to the right, the inner wall or shoulder 13 of the counterbore engages the thicker portion of the annulus 3 at the high point 15 thereof causing the edge 14 of the annulus at

the opposite side of the thicker portion to bite into the stock surface in gripping relation.

As long as the pusher tube 6 moves forward, the said edges 12 and 14 of the annulus will firmly grip the stock at substantially diametrically opposite points on its circumference.

It will be noted that with the parts in the position shown in Figure 2, the annulus or ring engages the shoulder 13 of the tube at only the 10 high point as at 15 when the tube is rotated and pushed forward. In this manner the grip of the annulus or the stock is maintained even when the speed of rotation of the stock is less than that of the tube such as when the forward end of the 15 stock engages the usual bar stop forwardly of the tube.

However, when the tube is moved in an opposite direction and the wall 13 is disengaged from the annulus, the bushing 4 will engage the opposite side of the annulus at 10 and thus release its grip on the stock, the annulus assuming the position shown in Figure 1. After the tube reaches its limit of motion in this direction, the parts are again in position to repeat the operation and 25 again move the stock forward.

While my invention is extremely simple, it is very effective in use and is materially inexpensive to manufacture.

With my invention it will be evident that the 30 bar stock can be removed with very little difficulty and effort and such removal does not require any disassembling of the machine itself. Furthermore, the pusher annulus or ring is always in position to grip the bar stock and to feed it forwardly without slipping. Another advantage resides in the ability, by this construction, to use 35 stock having a diameter very closely approaching that of the inside of the tube. I have found it possible to use stock having a diameter within 40 one-eighth inch of the inside tube diameter.

Various changes in the details of construction and arrangement of parts may be made without departing from the spirit of my invention or the scope of the appended claims.

45 I claim:

1. The combination with a stock feed tube for

screw machines, of a stock gripping device within the tube, said gripping device including an annulus having a portion of greater cross sectional area than any other portion thereof and responsive to the centrifugal forces set up by rotation of the tube, to automatically grip the stock during an axial movement of the tube in one direction.

2. The combination with a stock feed tube for 10 screw machines, of a stock gripping device within the tube and operable upon rotation of the tube to automatically grip the stock, said gripping device comprising an annulus having a maximum thickness at one point and a minimum thickness at a diametrically opposed point.

15 3. The combination with a stock feed tube for screw machines, of a stock gripping device within the tube and operable upon rotation of the tube to automatically grip the stock, a removable retaining member carried within the tube, said tube having an annular internal groove near its end and a resilient keeper ring removably seated in said groove, said gripping device including an annulus having a weighted portion and a stock gripping edge within said weighted portion.

20 4. A gripping member for intermittently gripping the bar stock in a feed tube of a screw machine, comprising an annulus the side walls of which lie in intersecting planes.

25 5. The combination with a stock feed tube, 30 of a stock gripping tube having a portion counterbored inwardly from its end to receive a stock gripping ring, of a stock gripping ring within the tube, said ring having a portion of greater cross sectional area than any other portion of the ring, said ring being responsive to the centrifugal forces set up by rotation of the tube to automatically grip the stock during an axial movement of the said tube in one direction, the wall 35 of said counterbored portion forming a shoulder with the internal wall of the gripping tube, said shoulder being adapted to engage said ring near its greater cross sectional area and thereby tilt the ring into gripping engagement with the stock.
